US0D1043241S

(12) **United States Design Patent** (10) **Patent No.:** **US D1,043,241 S**
(45) **Date of Patent:** **** Sep. 24, 2024**

(54) **WATER PITCHER**

(71) Applicant: **BRITA LP**, Oakland, CA (US)

(72) Inventors: **Russell E. Bell**, Pleasanton, CA (US); **Madeline A. Donovan**, Pleasanton, CA (US); **Rick T. Nishijima**, Pleasanton, CA (US); **David Wu Zhong**, Pleasanton, CA (US); **Scot Herbst**, Santa Cruz, CA (US); **Piercy Yau**, Causeway Bay (HK)

(73) Assignee: **BRITA LP**, Brampton (CA)

(**) Term: **15 Years**

(21) Appl. No.: **29/875,740**

(22) Filed: **May 9, 2023**

Related U.S. Application Data

(60) Continuation of application No. 29/825,617, filed on Feb. 3, 2022, now Pat. No. Des. 1,022,569, and a continuation of application No. 29/825,618, filed on Feb. 3, 2022, which is a division of application No. 29/752,565, filed on Sep. 28, 2020, now Pat. No. Des. 964,795, said application No. 29/825,617 is a division of application No. 29/752,565, filed on Sep. 28, 2020, now Pat. No. Des. 964,795.

(57) **CLAIM**

The ornamental design for a water pitcher, as shown and described.

DESCRIPTION

FIG. 1 is a perspective view of a water pitcher showing our new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a back view thereof.

The broken lines in the drawings depict portions of the water pitcher that form no part of the claimed design.
